UNITED STATES PATENT OFFICE.

FRANK CRAWFORD, SR., OF NEW BRUNSWICK, NEW JERSEY, ASSIGNOR TO THE CRAWFORD MANUFACTURING COMPANY, OF NEW BRUNSWICK, NEW JERSEY, A CORPORATION OF NEW JERSEY.

STOP MOTION FOR KNITTING MACHINES.

Application filed December 7, 1923. Serial No. 679,185.

My invention relates to certain improvements in stop motions, which are actuated when a thread breaks, or when a thread is under abnormal tension, due to a knot in the 5 thread, or when a thread catches on a bobbin.

The invention is especially adapted to machines for knitting stockings and other webbing of this type.

The object of my invention is to improve 10 the construction of the upper and lower mechanisms of the stop motion. One of these mechanisms governs the stop motion when abnormal tension is applied to a thread, and the other mechanism governs the stop motion 15 when a thread breaks.

In the accompanying drawings:

Fig. 1 is a perspective view illustrating 20 my improved stop motion, a portion of the knitting machine being shown in dotted lines;

Fig. 2 is a plan view of the upper mechanism with the cover plate removed;

Fig. 3 is a sectional view on the line 3—3, 25 Fig. 2;

Fig. 4 is a detached perspective view of a portion of Fig. 3;

Fig. 5 is a plan view of the lower mechanism with the cover plate removed, illustrating the mechanism in the "tripped" position; 30

Fig. 6 is a sectional view on the line 6—6, Fig. 5;

Fig. 7 is an enlarged plan view of the trip mechanism illustrated in Fig. 5, illustrating 35 the mechanism in the "set" position;

Fig. 8 is a side view of the mechanism illustrated in Fig. 7;

Fig. 9 is a sectional view on the line 9—9, Fig. 8;

Fig. 10 is a side view of one of the lower 40 thread guides;

Fig. 11 is a sectional view on the line 11—11, Fig. 10;

Fig. 12, is a plan view similar to Fig. 7, 45 with the trip arm removed;

Fig. 13, is a view similar to Fig. 12 with the parts released;

Fig. 14, is a plan view of the disk;

Fig. 15, is a plan view of the segmental 50 lever that controls the movement of the disk; and

Fig. 16, is a plan view of the segmental arm that engages the segmental lever.

Mounted on the portion 1 of the knitting

machine is a standard 2 which carries the 55 lower stop motion. Mounted on the casing of the lower stop motion is a standard 2^a which carries the upper stop motion.

The belt shifting mechanism 3 which is actuated by the stop motion is located on the 60 portion 1 of the knitting machine, and when actuated stops the mechanism of the knitting machine.

Mounted on the standard 2 is a bracket 4 having arms 5 on which the bobbins b are 65 mounted. The yarn a from each bobbin is threaded, as clearly shown in Fig. 1.

The lower stop motion mechanism is located within a casing 6 which is mounted on 70 the standard 2.

Radiating from the casing is a series of arms 7, which carry at their outer ends 75 thread guides 8, consisting of a fixed, U shaped plate 9 slotted as shown, and a movable trip plate 10 having fingers extending into the slots of the plate 9. The thread passes between the fingers and the plate and retains the trip plate 10 in position. Should a thread break, the movable trip plate is allowed to fall, actuating the lower mechanism 80 in the casing 6. This particular thread guide is illustrated in an application for patent filed by me on the sixth day of December, 1923, Ser. No. 678,967.

Each trip plate 10 is mounted on a rod 11, 85 carried by an arm 7 and extends into the casing 6. The rods are bent at right angles to form arms 12 within the casing.

The hub 6^a of the casing 6 is recessed to receive the upper end of the standard 2 and is 90 held in place by a set screw.

The hub is also recessed to receive the depending portion 86 of a plate 85 on which the trip mechanism is mounted.

Extending through the plate is a post 25. 95 On the upper end of the post is secured a disk 23, and secured to the lower end of a post is a shell 87 containing a coiled spring 88. One end of the spring is attached to the shell, and the other end is attached to the depending portion 86 of the plate 85. The spring imparts motion to the mechanism for stopping the machine when released.

The disk 23 is connected by a link 28 to an arm 29, a shifter rod 30, which has its bearing in the casing 6 and in a lug 31 on the bracket 4, Fig. 1. On the lower end of the rod is an arm 32 connected by a link 33 to a 100 105

bell crank lever 34 which actuates the belt shifter 3 of the machine.

A disk 13 is mounted on a pivot pin 14 adapted to a bearing 15 at the center of the casing. The end of the pivot pin rests on a screw 16, by which the disk can be adjusted vertically. The screw 16 is located in the part 25. Projecting from the under side of the disk 13 is a pin 17. This pin extends into a slot 18 in an arm 19, which is pivoted at 20 to the plate 85, and held yieldingly in position by a spring 21, mounted on the pin 20. On a downwardly projecting extension 19^a the arm 19 is rotatably mounted a roller 22, which bears against a disk 23 having a notch 24 to receive the roller. The disk 13 has a series of notches in its periphery located directly below the arms 12 of the rods 11, Fig. 5, so that if a rod is turned when a thread breaks, its arm will engage the disk 13 and will move it a distance to cause the disk to release the trip mechanism.

Pivoted at 36 on the plate 85 is a segmental arm 35, which is slotted at 37 and has a notch 37^b at one end of the slot. A segmental lever 38 is pivoted at 39 on the plate 85 and has a pin 37^a at its free end which extends into the slot 37 of the arm 35, as clearly shown in Figs. 7 and 13. In the lever 38 is a slot 40, into which extends a pin 41, which projects from the disk 23. The segmental arm 35 has a hook 42 at its outer end, arranged to be engaged by a hook 43 on the short arm 44 of a latch 45. The latch 45 is pivoted at 46 to the plate 85. The long arm 47 of the latch 45 lies in the path of the pin 17 and is bent downward at its outer end to be engaged by a projecting pin 48 on a trip spindle 49. On the pivot of the latch 45 is a spring 50 which bears against a fixed pin 51 and engages the latch 45, tending to hold the hook 43 yieldingly in engagement with the hook 42.

A projection 52 on the casing 6 forms a bearing for the trip spindle 49, Fig. 7. In order to locate the trip spindle properly in respect to the trip mechanism within the casing, a slidible beveled block 53 is provided, which can be moved into and out of contact with the portion 54 of the spindle.

When a stop motion is shipped from the factory, the block is raised and is secured in the raised position so as to hold the arm 48 of the spindle in proper relation to the lever 45. The screw that holds the block in position is released and the block falls to the position shown in Fig. 6. The trip spindle 49 is connected to a rod 55 leading from the upper mechanism shown in detail in Figs. 2, 3 and 4, the rod having an arm 56 within the casing 57. This arm is slotted, as shown in Fig. 2, and a pin 58 on a disk 59 extends into the slot so that, when the disk is moved, it operates the rod 55. The disk 59 is mounted on a spindle 60, which is located in a hollow standard 61, secured to the base of the casing

57, as shown clearly in Fig. 3. The end of the spindle rests on a screw 62, which can be adjusted to locate the disk properly in the casing. On the upper end of the standard is a bracket 63, secured thereto by a set screw 64. On this bracket is a spring plate 65 having a portion that bears upon the center of the disk and prevents any vertical movement of the disk, yet allows it to turn freely.

Depending from the periphery of the disk 59 is a flange 66, in which is a series of recesses 67. In the recesses are located the arms 68, which are secured to the rods 69 that radiate from the casing under the arm 70. On the outer ends of these rods are hooks 71, over which the threads pass from the lower thread guides 8 to the perforated ring 72 on the standard 2^a. The threads pass from this ring to the knitting machine.

On the arms 70 are fingers 73, which extend 85 over the hooks 71. The outer ends of the hooks rest against the fingers, when in the raised position. Should excessive tension be exerted on the thread, then the hooks are drawn down and the arm 68, on the particular rod 67, turns the disk 59. This disk, when turned, actuates the rod 55, causing the mechanism in the lower casing 6 to be tripped, which stops the knitting machine.

Means are provided for adjusting the tension of the rods 69 individually. By having the independent adjustments, the mechanism can be adjusted for yarn of different weights. In some instances, light and heavy yarns are used in the same machine at the same time. 100

The arm 68, in the present instance, is made by twisting a wire into shape and securing it to a rod 69, as shown in Figs. 3 and 4. The opposite end of the wire is bent to form a second arm 74. At the end of the arm 74 is an eye, and engaging the eye is a coiled spring 75. The opposite end of the spring is connected to a lever 76, pivoted at 77 to a bearing on a plate 78, secured to the casing 57. The lever is made as shown clearly in Fig. 4. Pivotally mounted on the lever is a nut 79 through which extends a screw 80. The screw extends through an opening in the bottom of the casing 57 and has a head 81, located outside of the casing. Between the casing and the nut 79 is a spring 82. By turning the screw, the tension on the rod, to which it is connected, can be regulated.

The operation is as follows: The yarn from the bobbins is threaded through the lower thread guides 8, then over the hooks 71 of the upper mechanism and through the ring 72 to the knitting machine. When the machine is set in motion, the thread passes freely through the guides of both sets. In event of one of the threads breaking the arm 10 which normally is held vertical by that particular thread is released, causing the rod 11 attached thereto to be turned. Turning of the rod 11 causes the arm 12 thereon to engage the side 120 125 130

of one of the recesses in the plate 13, causing subsequent movement of the plate 13 and the pin 17 thereon in a clockwise direction, as viewed in Fig. 7. The roller 22 on the arm

5 19 at this time is moved into the recess 24 in the disc 23 by means of the pin 17 engaging one side of the slot 18 in the arm 19. The said movement of the pin 17 causes the said pin to engage the latch 45, turning it on its 10 pivot and releasing the hook 43 thereof from the hook 42 of the lever 35.

The normal tendency of the disc 23 is to turn in a counter-clockwise direction under the influence of the spring 88, such tendency 15 being restricted by the pin 37^a normally occupying a position in the notch 37^b, in the lever 35, and the pin 41 on the disc 23 being held by the slot 40, of the lever 35.

When the hook 43 of the latch 45 is released from the hook 42 of the lever 35 the lever 35 immediately swings on its pivot and the pin 37^a rides out of the notch 37^b and toward the opposite end of the slot 37, in the lever 35. This movement of the pin 37^a permits the lever 38 to swing on its pivot and the pin 41, of the disc 23, to move in the slot 40, of the lever 38, to the opposite end thereof, from its normal disc retaining position. The disc 23 moves in a counter-clockwise direction and through the link 28 and lever 29 turns the rod 30 in a clockwise direction, to actuate the stop motion of the knitting machine. The said rotation of the disc 23 causes the side wall of the recess 24 therein to engage the roller 22 and move the arm 19 in a counter-clockwise direction to the position illustrated in Fig. 5, the side of the slot 18 in said arm 19 engaging the pin 17 of the disc 13, thereby moving the said disc 13 in a counter-clockwise direction. The disc 13, in moving, engages the arms 12 and the rods 11 are rotated thereby to restore the thread engaging fingers 10 to their normal positions for rethreading.

45 To reset the mechanism, the rod 30 is moved in a counter-clockwise direction and through the lever 29 and link 28 moves the disc 23 in a clockwise direction, the pins 41 moves in the slot 40 restoring the lever 38 to its normal position, the pin 37^a thereon moving within the slot 37 into the notch 37^b in the lever 35, thereby restoring the hook 42 of said lever 35 in locked engagement with the hook 43 of the latch 45.

55 When the disc 23 moves as above described, to reset the mechanism, the recess 24 therein moves into alignment with the roller 22 of the lever 19 in order to permit subsequent tripping of the mechanism when another 60 thread breaks.

If a thread should be caught, or excessive tension be applied to the thread, then the hooks 71 are drawn down. This movement causes the disk 59 to be turned, which imparts motions to the vertical shaft 55 that

connects the two stop motions. An arm on the lower end of this shaft trips the lower stop mechanism, which stops the machine through the rod 30, as above described.

Thus, it will be seen that the upper and 70 lower stop motions act upon the trip mechanism, which releases the stop mechanism that controls the mechanism that stops the knitting machine. Adjusting means for varying the tension on each arm of the upper stop 75 motion enables the operator to use yarns of different weights.

I claim:

1. The combination in a stop motion, of a casing; arms radiating from the casing; a 80 rod carried by each arm, each rod having a finger at the outer end over which the thread passes; an arm at the inner end of each rod; trip mechanism common to all of the rods and adapted to be directly operated 85 by any one thereof; and means for independently adjusting the tension of each rod.

2. The combination in a stop motion, of a casing; a series of arms on the casing; a 90 rod mounted on each arm and having a finger at its outer end; an arm on the inner end of each rod; a slotted disk arranged to be turned by the said arm when a thread is under excessive tension; a second arm on each rod; a 95 spring attached to said arms; a lever secured to the opposite end of the spring and pivoted to the casing; and means for adjusting the lever to regulate the tension on the rod.

3. The combination in a stop motion, of a 100 casing; a series of arms on the casing; a rod mounted on each arm and having a finger at its outer end; an arm on the inner end of each rod; a slotted disk arranged to be turned by the said arm when a thread is caught; a 105 second arm on each rod; a spring attached to said arms; a lever secured to the opposite end of the spring and pivoted to the casing; a swiveled nut on the lever; a screw extending through the casing and through the nut; and a spring between the nut and the casing so that, on turning the screw, the lever can be adjusted to regulate the tension on the rod.

4. In combination with mechanism adapted 115 to be tripped, to stop a knitting machine, a stop motion comprising a standard attached to said knitting machine; a lower casing on the upper end of said standard; a second standard detachably secured to the top of 120 said lower casing; an upper casing secured to the upper end of said second standard; a series of thread guides on said lower casing; a trip rod rotatably mounted in said lower casing and extending therefrom in a 125 position substantially parallel to and spaced apart from said first standard; means in said lower casing including a latch operable by said thread guides for actuating said trip rod when a thread breaks; a short spindle rotatably mounted on the outside of said lower 130

casing; an arm on said short spindle extending into said lower casing and adapted to engage said latch; actuating means in said upper casing adapted to be operated when a thread becomes abnormally taut; a trip spindle detachably and operatively connecting said short spindle with the upper casing actuating means, disposed in a position substantially parallel with and spaced apart from said second standard; and means for operatively connecting said trip rod with the stop mechanism of the knitting machine.

5. The combination in a stop motion, adapted to be applied to a knitting machine, of supporting standards having upper and lower casings attached thereto; actuating means in each casing; a trip rod controlled by the actuating means of the lower casing; a latch controlling said lower casing actuating means; a trip spindle controlled by the actuating means of the upper casing; a lever on said trip spindle adapted to engage said controlling latch in the lower casing and having a hub provided with a flat side; a 15 wedged shaped block slidably mounted in said lower casing and adapted to be moved into engagement with said flat side of the hub; and means for maintaining said wedge block in either its hub engaging or disengaging position, for maintaining the elements of the stop motion in their correct relative positions, when said stop motion is detached from a knitting machine.

6. The combination in a stop motion of a lower supporting standard; a lower casing on said lower standard; an upper standard detachably secured to said lower casing; an upper casing on said upper standard; actuating means in said upper casing adapted to be operated when a thread becomes abnormally taut; actuating means in said lower casing adapted to be operated when a thread breaks and comprising a movable cam disk; a link pivoted to said cam disk; a trip rod spaced apart from said lower standard and having an arm pivotally attached to said link; a second movable disk operable by thread guides on said lower casing; a lever

pivoted in said lower casing operatively connected to said second disk; a roller on said lever adapted to be engaged by said cam disk; a pin on said cam disk; a segmental lever pivoted in said lower casing and engaged by said pin; a pin on said segmental lever; a segmental arm pivoted in said lower casing and engaged by said segmental lever pin; a hook on said segmental arm; a latch pivoted in said lower casing and having a hook portion adapted to engage the hook of said segmental arm; a pin on said second disk adapted to engage said latch; a trip spindle spaced apart from said second standard and operable by the actuating means in said upper casing; a lever on said trip spindle adapted to engage said latch in the lower casing; and means for operatively connecting said trip rod with the stop mechanism of a knitting machine.

7. The combination in a stop motion of a lower supporting standard; a lower casing on said lower standard; a trip rod extending from said lower casing, operatively connected to the stop mechanism of a knitting machine and spaced apart from the said lower standard; means in said lower casing adapted to be actuated by thread guides on said lower casing when a thread breaks, and thereby subsequently operate said trip rod; a controlling latch included in said lower casing actuating means; an upper supporting standard on said lower casing; an upper casing on said upper standard; a series of arms on said upper casing; a rod mounted on each arm and having a finger at its outer end; an arm on the inner end of each rod; a slotted disk in said upper casing adapted to be directly engaged and turned by said arm when a thread becomes abnormally taut; a trip spindle spaced apart from and substantially parallel with said upper standard; a lever on said trip spindle; a pin on said slotted disk engaging said trip spindle lever; and a lever on said trip spindle adapted to engage the said controlling latch in said lower casing.

FRANK CRAWFORD, SR.
